CONSTRUCTION MATERIAL

Anthony J. Pfohl, Cincinnati, Ohio, assignor to
 The Philip Carey Manufacturing Company, a
 corporation of Ohio

Application March 25, 1929, Serial No. 349,541

6 Claims. (Cl. 72—124)

My invention relates to construction material. It is addressed to a construction material while capable of being moulded into any desired form, cut into desired lengths and possessing the qualities of being adapted to absorb shocks, withstand weight, is waterproof, dustless, will not crack and will knit or heal under traffic.

It is suitable for many construction purposes, forming a suitable wearing surface for industrial 10 warehouses, loading platforms, machine shops, textile mills, garages and many other uses.

In the drawing I have shown a perspective view of a piece of lumber embodying my invention.

My improved construction material is formed 15 preferably from a composition containing bituminous and other materials such as mineral particles, fibrous materials, etc. These materials are suitably mixed and are formed into any desired shape, preferably by extrusion, using the method 20 and means described in my co-pending application, Serial No. 39,619 filed June 25, 1925.

In the manufacture of my construction material I mix bituminous material such as asphalt and a filler of fibrous material and mineral material 25 in the presence of heat so as to form a homogeneous mass which is then passed through an extruding machine such as that referred to in the above mentioned application, thereby compacting the mass and forming it into the desired 30 shape which operation is carried out while the material is warm. It is then allowed to cool and is ready for use. I have found that a very satisfactory construction material is obtained by taking the waste products from the manufacture 35 of prepared roofing, either plain or mineral surfaced, and any other waste saturated felt materials, mixing those with additional asphalt if there is not sufficient asphalt in them, adding if desired additional mineral or fibrous material, or both, masticating these waste materials in the presence of heat until reduced to a suitable plastic 40 state when they are extruded by being forced through a die having an orifice of the desired shape so that the material will completely fill the orifice in its passage therethrough and will retain 45 the shape of that orifice after passing out from the same.

My improved construction material can be made very hard by the addition of mineral or by using 50 an asphalt that is hard at normal temperatures. In my improved product the body has an outer surface in the nature of a shell B extending inward for some distance that is of greater density and is harder than the heart C of the product. 55 The depth of this shell may be regulated by the

amount of compression used or by the density of the plastic mass from which the material is being formed, or both, in forming the product, that is, if a shell of great depth is desired greater pressure is used or a plastic mixture of greater density, or both, is used.

I have found that in manufacturing my product if it is desired to increase the hardness of the shell and its depth I can do so by adding additional mineral or fibrous material or both. Such an addition gives a greater density to the homogeneous batch and I have noticed the greater the density of the batch the harder the resultant product, and that by subjecting the batch to greater pressure during the forming process the outer portion or shell like portion becomes denser and the thickness of the dense hard portion increases with the increase in the pressure. While I have shown and referred to the one method of manufacture by extruding the material, any method that would give the resultant product desired would be satisfactory.

My improved product consists preferably of a homogeneous mixture of bitumen, fibrous material or fibres of any suitable nature, and particles of mineral such as granules of slate or like mineral, fine sand or pulverized mineral, any combination of these minerals, formed into a construction material substantially of the same character throughout except that the outer portion is of a more dense character than the center.

I claim:—

1. A preformed construction product having the same materials throughout, said materials consisting of a homogeneous mixture of bituminous, 90 fibrous and mineral materials, said product having the outer portion harder than the interior.

2. A preformed construction product having a shell like outer portion of greater hardness than the interior, said shell and said interior formed from a homogeneous mixture containing asphalt hard at normal temperature and scrap felted materials.

3. A preformed construction product having a shell like outer portion of greater hardness than the interior, said shell and said interior formed from a homogeneous mixture containing asphalt hard at normal temperature and scrap felted materials and granular mineral materials.

4. A preformed construction product, composed 105 of a bituminous material, a mineral material and a fibrous material, preformed to the desired shape and having a portion of said product of greater density and hardness than the adjacent portion, said portions being integral.

2

1,952,210

5. A construction product, composed of a homogeneous mass of bituminous, fibrous and mineral particles, preformed to the desired shape and having a shell like portion of greater density than the interior portion, said shell like portion and interior portion being formed of a plurality of materials, said product constituting a unitary product.

portion of greater density than the interior portion, said shell like portion and interior portion being formed of a homogeneous plastic mixture of a plurality of materials, said product constituting a unitary product.
